UNITED STATES PATENT OFFICE.

WILLARD C. AVERILL, JR., OF HOUSTON, TEXAS.

APPARATUS FOR SEPARATING HYDROCARBONS.

Application filed October 7, 1922. Serial No. 593,084.

To all whom it may concern:

Be it known that I, WILLARD C. AVERILL, Jr., a citizen of the United States of America, and a resident of the city of Houston, 5 county of Harris, State of Texas, have invented certain new and useful Improvements in Apparatus for Separating Hydrocarbons, of which the following is a description.

One object of my invention is to obtain 10 a clean separation of low boiling hydrocarbons from high boiling hydrocarbons both economically and rapidly.

A second object of my invention is to obtain an additional refining of the low 15 boiling hydrocarbons simultaneously with their separation from the high boiling hydrocarbons.

The novel features of my apparatus are pointed out with particularity in the ap- 20 pended claims. The invention itself, how- ever, with further objects and advantages, will best be understood by reference to the following description, taken in connection with the accompanying drawing in which—

25 The figure is a schematic representation, partly in section, somewhat diagrammatical, of an apparatus arranged according to my invention.

In the drawing 1 indicates a still into 30 which crude petroleum or like oil is introduced by pump 1^a, through pipe 1^b. Preferably the pipe 1 is coiled within the still below the oil level therein so that the incoming oil is heated approximately to the 35 temperature of the oil in the still before being discharged from the pipe. The oil is supplied from pipe 1^b into pans 2 under pressure sufficient to prevent the water in the oil changing into steam within the pipe

40 1^b. The upper portion of the pipe 1^b is perforated as indicated and the water consequently suddenly vaporizes into steam above the pans 2, thereby atomizing the oil, and assisting in the liberation of gasoline 45 and like low boiling ingredients of the hydrocarbon being distilled. Separation of steam and light hydrocarbons from heavy hydrocarbons is further promoted by the pans 2 into which the unvaporized hydro-

50 carbons fall from the pipe 1^b and from which they continue to overflow from one to the other until they unite with the body of liquid in the lower part of the still.

55 Vapors of the hydrocarbons of the desired specific gravity and above a definite vaporization point being distilled off, to-

gether with water vapor, pass out of the still 1 through a large upwardly inclined pipe 3 which delivers the vapors into a tower-like dephlegmator 4, which may be packed with 60 any suitable material, broken coke, brick, stone ware, or the like answering the purpose. In practice, I have found it desirable to use a plurality of small iron pipe sections 4' arranged within the dephlegmator 65 as shown. A portion of the hydrocarbon vapor condenses in tower 4 and drops to the bottom of the tower accompanied by some water. At the bottom of the tower 4 is a water draw-off leg 5 with an automatic 70 drain trap 5^a having vent 5^b, drain 5^a acting to allow the water to be discharged continuously. From the top of the draw-off leg 5, where the entrapped liquid hydrocarbons float a pipe 6 leads off to circulating 75 pump 6^a which pumps the hydrocarbon condensate through spray 7 at the top of the tower 4. This condensate then comes into contact with the ascending vapors and has the effect of removing from these vapors 80 a large portion of the high boiling oils or heavy ends. This operation is continuous and by means of the circulating pump the oil is exposed many times to the ascending vapors and an excellent separation of high 85 boiling point material or heavy ends from low boiling point material or lighter ends is obtained.

This feature of my improved apparatus is particularly important and is a new de- 90 parture from the prior practice in refining hydrocarbons. Heretofore, the practice has been to allow the condensate to come into contact with the rising vapors to collect the heavy ends so that they may be returned to 95 the still. On the contrary in my apparatus the vapors from the still pass through the falling condensate repeatedly after separation from the water so that when the vapors have the upper portion of the dephlegmator 100 4, they carry substantially all of the lighter hydrocarbons which the original oil contained. This has been found to increase the production of gasoline obtained from Mexican oils by approximately 50 percent. 105

Uncondensed vapors are led off from the upper part of tower 4 and delivered into the lower part of a second tower 8 by means of pipe 8^a. Tower 8 is also preferably packed with material inert to the hydro- 110 carbon and steam vapors, such as that mentioned in connection with tower 4. From

the lower part of tower 8, a pipe 9 leads back to the lower part of tower 4, this pipe 9 inclining downwardly from tower 8 to tower 4 whereby condensed hydrocarbons 5 are back trapped through pipe 9 to tower 4. The condensate from tower 8 is then circulated through the tower 4 by pump 6^a along with the condensate from tower 4. Tower 8 may also have a spray 10 in its upper 10 portion whereby water is introduced at the top of tower 8 for regulating the temperature. Water is removed from the bottom of tower 8 through draw-off leg 11 and overflow pipe 11^a, this pipe having a vent 15 11^b.

Hydrocarbon or oil vapors are removed from the upper part of tower 8 through pipe 12 and may be condensed in a condenser 13.

By regulating the speed of the circulating 20 pump 6^a and assuming a substantially constant water temperature, the amount of water supplied through sprayer 10, a distillate of any desired end point results.

The very heavy condensates which are 25 separated out flow back through vapor line or pipe 3 to the still, the pipe 3 being inclined downwardly from the tower 4 to the still in order to permit the heavy liquid to thus flow back.

30 High boiling liquid residue is removed from still 1 through pipe 14, having vent 14^a, the pump 15 drawing off the liquid it is desired to remove through pipe 14.

The effect of my invention is that a very 35 excellent separation of gasoline is obtained at one operation, whereas ordinarily two distillations are necessary. I am thus able to save the expense and material losses which naturally result from two distillations as 40 compared with one. My invention is also applicable to either light or heavy oils, and any desired cut can be obtained, with sharp separation, as indicated above.

While I have illustrated and described the 45 preferred embodiment of my invention and the preferred method of operating the same, I do not wish to be limited to details of construction, arrangement or operation here-

in disclosed, except in so far as such details are essential to the novelty of the appended 50 claims.

Having thus described my invention I claim:

1. A petroleum distilling and refining apparatus comprising in combination, a still, 55 a dephlegmator, a vapor line connecting said still with the lower portion of said dephlegmator, a draw-off and water separator connected with the lower end of said dephlegmator, means for withdrawing condensate 60 from said separator and spraying the same into the upper part of said dephlegmator, and means for withdrawing vapor from the upper portion of said dephlegmator.

2. A petroleum distilling and refining apparatus comprising in combination, a still, 65 a dephlegmator, a vapor pipe connecting said still with a point near the bottom of said dephlegmator, said pipe being downwardly inclined to provide a return of the condensate above a definite level, a draw-off and water separator connected with the lower end of said dephlegmator, means for withdrawing condensate from said separator and spraying the same into the upper 70 part of said dephlegmator, and means for withdrawing vapor from the upper part of said dephlegmator.

3. A petroleum distilling and refining apparatus comprising in combination, a still, 80 a dephlegmator, a vapor line connecting said still and dephlegmator tower, a water separator connected with said dephlegmator, means for withdrawing the condensate from said separator and spraying it into the upper portion of said dephlegmator, a second tower, a connection for carrying vapor from the first tower to the second tower, means for supplying a water spray at the upper 85 portion of said tower for washing said vapor, a connection for returning hydrocarbon condensate from the second tower to the dephlegmator and a vapor condenser connected with the second tower.

WILLARD C. AVERILL, JR.
